UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

DESIGN FOR A FRONT AUTOMOBILE FENDER.

Application filed August 23, 1927. Serial No. 23,183. Term of patent 14 years.

To all whom it may concern:

Be it known that I, JOSEPH LEDWINKA, a citizen of the United States, residing at Philadelphia, in the county of Philadelphia, State of Pennsylvania, have invented a new, original, and ornamental Design for a Front Automobile Fender, of which the following is a specification, reference being had to the accompanying drawings, forming part thereof, wherein—

Figs. 1 and 2 are perspective views of an automobile fender embodying my new design as viewed respectively, from the front and from the rear.

Fig. 3 is a top plan view thereof.

Figs. 4 and 5 are sectional views taken respectively, on the lines 4—4 and 5—5 of Fig. 3.

I claim:

The ornamental design for a front automobile fender, as shown.

Signed at Philadelphia, in the county of Philadelphia, in the State of Pennsylvania, this 12 day of August, 1927.

JOSEPH LEDWINKA.
